UNITED STATES PATENT OFFICE.

ALEXANDER H. MATHESIUS, OF BROOKLYN, NEW YORK.

WIRE-ROPE GRIP.

SPECIFICATION forming part of Letters Patent No. 423,694, dated March 18, 1890.

Application filed December 6, 1883. Serial No. 113,669. (No model.)

To all whom it may concern:

Be it known that I, ALEXANDER H. MATHESIUS, of Brooklyn, county of Kings, and State of New York, have invented certain new and useful Improvements in Wire-Rope Grips, of which the following is a full, clear, and exact description, reference being had to the accompanying drawings, and to the letters and figures of reference marked thereon.

10 My invention has relation to that class of devices employed for connecting cars with moving wire ropes or cables by which the cars are propelled, such devices being ordinarily known as "wire-rope grips" or "cable-grips."

15 The object of my invention is to produce a simple, compact, durable, and effective grip of the character above named, by use of which the cable may be securely clamped without

20 danger of slipping or damage to the cable or grip, wherein the cable and grip may be easily and quickly located, so as to assume their proper working positions with respect to each other, to adapt the grip for use in connection 25 with either surface or tunnel cables, and to secure all the advantages of the die-grip and roller-grip in one apparatus.

To secure these advantages and others my improvements involve certain novel and useful arrangements or combinations of parts, peculiarities of construction, and principles of operation, all of which will be herein first fully described, and then pointed out in the claims.

35 In the accompanying drawings, forming part of this specification, Figure 1 is a side elevation, Fig. 2 a top or plan view, and Fig. 3 an end elevation and partial section, of a grip constructed and arranged for operation 40 in accordance with my invention, parts being broken out in each figure to facilitate the illustration. Fig. 4 represents an edge view, top view, and cross-section of the movable die, and bottom and end view of the adjusting-nut applied therein. Fig. 5 represents a side view and plan of the lever-connections for closing and opening the grip. Fig. 6 is an elevation showing an arrangement of parts for elevating the rope or cable to the grip; 45 Fig. 7, a sectional elevation of the same arrangement, showing the elevating-wheel turned to one side; and Fig. 8, a top or plan

view. Fig. 9 is an elevation intended to show a form of lazy-tongs and various means of transmitting movement thereto for the purpose of elevating and lowering the grip or opening or closing the grip. Fig. 10 is a plan of a fragment of the adjustable die-plate, showing how the same may be operated by an eccentric instead of by the link and pin shown in Fig. 5. Fig. 11 is a section of a fragment of one of the rollers or dies and the rope located therein, showing how the roller or die may be cut or formed under some circumstances. Fig. 12 represents an end view and a top or plan view of means adapted to operate the grip when used in connection with a rope running in a tunnel, and an elevation of lever and toggle for transmitting motion to the grip-operating devices. Fig. 13 is a cross-section and partial elevation of the grip upon a scale enlarged beyond previous figures, the view being taken upon a plane passing through one of the sustaining-screws. Fig. 14 is a perspective view of a fragment of the grip, showing the arrangement of the die and the top and bottom plates operating in connection therewith.

In all these figures like letters and figures of reference, wherever they occur, indicate corresponding parts.

A represent the frame, of any approved size and form, the same being substantially braced and properly secured beneath the car, as by arms B B.

85 C C and C' C' are the rollers of the grip, and D D' the dies thereof, the dies being located between the rollers and all mounted upon the jaws E E, which approach and recede from each other in order to effect the 90 clamping and unclamping.

F F are cylindrical uprights serving to guide the gripping mechanism in its up-and-down movements, the uprights passing through suitable openings in the guide-blocks 95 H H, which are rigidly secured to the string-pieces G G, the string-pieces being secured to the links 30, and by them to the grip proper.

I is a cross-piece, from which the gripping mechanism is suspended by means of bolts or rods I' I', of which the lower ends are secured to the links 30 and the upper ends to cross-piece J, the bolts being supplied with suitable nuts for regulating the height of the grip and

maintaining it in any place to which it may be adjusted.

K is a connecting-rod, which unites the cross-piece I with a crank K' upon a horizontal shaft K². By revolving the shaft K² it is plain that the grip will be made (through its connection with the shaft) to rise or fall, according to the direction of rotation of the shaft.

10 Various means may be adopted for rotating the shaft according to circumstances—as, for instance, a simple lever, as K³, shown at the right, or a pair of bevel-wheels, as at K⁴ K⁴, and shaft K⁵ at the left of Fig. 1; or any other 15 suitable mechanical appliance may be adopted for the purpose.

The grip is opened, then lowered by the means above described until it embraces the cable, then partially closed and elevated to its 20 proper position, carrying the cable with it. The advantages of thus connecting with the cable, raising it by means applied to or on the car, and dispensing with other appliances independent of the car will be readily appreciated.

25 Each of the jaws E is provided on its upper face with a central perforated lug 20 and with perforated ears 21, disposed in line with said lug a short distance therefrom, and a bolt e extends through said lugs and ears.

30 The two jaws E are connected by coupling-links 30, hinged at their opposite ends to the bolts e, between the central lug and the ears, said bolts constituting the pintles on which the jaws swing, as shown in Fig. 1. A horizontal lever M is fulcrumed to the lug of one of the jaws E, and a horizontal thrust-screw N is secured to the lug in the other jaw. The inner end of the lever M is provided with an anti-friction roller m, which bears against the 35 head of the thrust-screw N.

A link N' is connected at one end with the lug containing the thrust-screw and at the other end with the inner end of the lever M, as indicated by dotted lines in Fig. 3. The perforations through the link 40 N', by which its ends are fastened to the lug and lever, are made oblong, in order that the jaws may move freely when the lever M is actuated, as described in my patent, No. 287,451, dated October 30, 1883. The lever M is in-

45 tended to be extended to any convenient position and to be moved by any suitable mechanism. The head of the thrust-screw N has a reversed curve, as shown in Fig. 5, the curve being struck with a radius equal to the dis-

50 tance from the bearing-point of wheel m to the center of the fulcrum about which lever M turns. The link N' connects one of the hinged jaws with the inner end of lever M, so that by shifting the lever from side to side 55 the two jaws are compelled to move.

55 L L are guide-rollers mounted in the string-pieces G G, one on each end of the grip. The axes l l of these rollers are eccentrics, and are made to turn upon bolts, as l' l', by which 60 they are clamped and held in any position to which they may be adjusted. By suitably adjusting the axes upon the bolts the rollers

are made to run at the required level. These rollers are for the purpose of preventing the grip from being lowered too far, (as they will 70 arrest the descent of the grip as soon as they strike the cable,) and also to direct the cable so that it will run in perfect line between the rollers and dies of the grip, thus constituting a perfect guide. For this purpose the rollers 75 L L are grooved to accommodate the cable and thus keep it in line between them. In case the cable is elevated to the grip these rollers L L will prevent it from being carried up too far, and thereby enable the cable to be 80 properly located in the grip by automatic cable-lifts.

The rollers C C and C' C' are grooved for the accommodation of the cable, and the lower parts of these grooves are scored or otherwise 85 formed to correspond with the outer surface of the cable. I score only the lower parts, leaving plain spaces at or near the outer margins of the grooves, so as to obviate damage to the cable or wear upon the rollers. The 90 scoring is represented at c and the plain parts at c'. The purpose of the scoring is to prevent slipping of the rope after the roller is clamped thereon. A scoring of a die was shown in my previous patent above named, 95 wherein the die was made movable in ways provided for it. According to this part of my invention I score the roller, which turns upon a central axis, or otherwise provide the rollers with a scored bearing for contact with 100 the cable. This feature is applicable upon any form of roller-grip, or grip wherein rollers are employed, and it will be observed that it is not dependent upon any means of suspending the grip.

105 The means shown for operating the grip will (so far as they are alone concerned) be quite as effective in case the scoring be omitted or in case the die or roller be made as in Fig. 11, so that the rope or cable O will wedge 110 into the groove provided for it in the wheel or die represented at C².

Die D' is fixed to its jaw and moves as its 115 jaw moves, but its opposite or mate receives its motion partly through the medium of the jaw with which it is connected and partly through the medium of a crank or eccentric, which is fitted to the lower end of a shaft M', and which is guided by a suitable perforation in the jaw. The movable die is composed of 120 a center plate d, which is an extension of the bearing-face of the die, and top and bottom plates d' d'. The center plate is perforated to receive the link b, of which one end is fitted to the lower end of shaft M' and the 125 other end to plates d' d' by pin b'. Adjusting-nut g' is also fitted to plates d' d'. Set-screw g passes through the center plate and enters the adjusting-nut g'. Link b being held at one end by the lower end of shaft M', which is guided by jaw E, and at the other end by pin b', which connects plates d' d', it 130 is evident that if set-screw g is turned in a manner to screw it into adjusting-nut g',

which is connected with plates $d' d'$, it will advance the bearing-face of the die toward the rope or cable. The plates $d' d'$ are held in place and connected with the jaw by screw-bolts, which pass through slots in the plates and enter the jaw, the arrangement being such that the plate d may move between $d' d'$ and the upper face of upper plate d' move on the lower face of the jaw.

Depending from lever M is a shaft M' , secured to said lever, as by a key a , and having its lower part cut away to form a crank or eccentric f , (see Fig. 5,) upon which is applied a link b for moving the adjustable plates d' . The arrangement is such that as the lever is shifted toward either side the link b will draw the bearing-face back from contact with the cable; but while the lever is in its central position and before it is shifted to one side far enough to remove its roller m from contact with the reverse curve of thrust-screw N the face d will be forced more or less into contact with the cable.

The pin b' enters the perforations b^2 in the plates d' and connects the link therewith. Instead of using the link and pin, the end of shaft M' might be made to directly enter a slot prepared for it in the sliding plates, as indicated in Fig. 10. Being thus arranged, the rollers $C C' C' C$ are forced into contact with the cable by shifting lever M toward its central position, and the car is forced to gradually acquire the speed of the cable. When this takes place, further shifting of the lever closes plate d against the cable, and the latter is then securely clamped between the dies, and there can be no possibility of slipping.

When required to release the cable, the dies are first released by shifting the lever M , and then the rollers are released by further shifting. This successive action takes place without special attention on the part of the operator, who has only to move the one lever for the purpose of properly tightening or loosening the grip.

In Fig. 9 the jaws $E' E'$ are supposed to carry the gripping mechanism. They are operated by a lazy-tongs, as plainly shown, which means may be applied under some circumstances. By applying the power through the medium of a rod, as at h , the same power will produce more working effect in closing than in opening the jaws, and the reverse by applying it through a rod, as h' . A rod, as h^2 , may be applied to secure advantages in the direction of movement. The lazy-tongs are advantageous on account of the many different directions from which the power may be applied, and they are specially advantageous for operating the grip in the tunnel systems. In these systems compactness is essential. The grip may be arranged substantially as indicated in Fig. 12, wherein the jaws $E' E'$ (supposed to carry the gripping mechanism)

are operated by a lever moving directly over the grip, rather than at one side of it, as in Fig. 3.

M^2 represents the operating-rod, by raising and lowering which the jaws are moved. It is connected by any suitable toggle-joint n with lever M , (the side extension of which is omitted,) and this joint is hinged, as at n' , so as to permit the jaws to swing.

In Figs. 6, 7, and 8, P is an elevating-roller for lifting the cable O to the grip. It is hung upon an arm p , journaled in a swinging shaft p' , which is hinged, as at p^2 . This cable-raising mechanism may be affixed to the car or to the grip thereunder in any suitable way, or it might be arranged at any convenient part of the track. By swinging the shaft p' it is plain that the cable will be raised. It is then clamped by the grip, when the wheel P must be swung to one side to get it out of the way. For this purpose the arm p is journaled in shaft p' , as at p^3 , and is supplied with a lever p^4 , by which it may be swung to one side. The lever for swinging may be variously applied.

The mechanism constructed and arranged substantially as above set forth will be found to be effective, durable, and not liable to get out of order, and generally to answer all the purposes or objects of the invention, as before set forth.

Having now fully described my invention, what I claim as new, and desire to secure by Letters Patent, is—

1. The herein-described gripping-roller, the groove in which is scored at the bottom part, leaving plain margins, substantially as shown and described.

2. The guiding-rollers hung upon adjustable axes and combined with the gripping mechanism, substantially as shown and described.

3. A die composed of a center plate d , provided with a bearing-face, and the top and bottom plates d' , an adjusting-nut g' , connected to the plates d' , and a set-screw g , passing through the center plate and entering the adjusting-nut.

4. In a cable or wire-rope grip, the gripping mechanism suspended and guided substantially as explained, and a connecting-rod and revolving shaft combined with said gripping mechanism for raising and lowering the same, substantially as and for the purposes set forth.

5. In combination with the jaws carrying the gripping mechanism, the lazy-tongs applied thereto for moving the same, substantially as and for the purposes set forth.

In testimony that I claim the foregoing I have hereunto set my hand in the presence of two witnesses.

ALEXANDER H. MATHESIUS.
